UNITED STATES PATENT OFFICE.

JOHN THOMAS, OF NEW YORK, N. Y.

LEVER-CHECK FOR ELECTRIC CONTROLLERS.

No. 919,089.

Specification of Letters Patent. Patented April 20, 1909.

Application filed January 27, 1909. Serial No. 474,543.

To all whom it may concern:

Be it known that I, JOHN THOMAS, a subject of the King of Great Britain, and a resident of the city of New York, borough of Brooklyn, in the county of Kings and State of New York, have invented a new and Improved Lever-Check for Electric Controllers, of which the following is a full, clear, and exact description.

10 This invention relates to electric controllers such as used on electric cars for controlling the operation of the motor.

It is a well-known fact that damage is frequently done to motors by turning the full 15 strength of the current through them suddenly, due to the fact that the motors have not generated a counter-electromotive force which will overcome part of the current. It has been attempted to overcome this difficulty, by using circuit arrangements which 20 will give series or parallel connections in different positions of the controller lever.

The object of the present invention is to 25 provide means for checking the controller lever, which will operate so as to prevent its being suddenly rotated in a direction which will throw on the full strength of the current. The device operates in such a way that while 30 it does not prevent the lever from being moved into the position which will turn the current on, it does prevent its being swung to that position by a single continuous advancing movement. In this way even if the controller lever is in the hand of an unskilled 35 motorman, it will be impossible for him to turn the current on suddenly, to the injury of the motor as suggested.

40 The invention consists in the construction and combination of parts to be more fully described hereinafter and particularly set forth in the claims.

Reference is to be had to the accompanying drawings forming a part of this specification, in which similar characters of reference indicate 45 corresponding parts in all the figures.

Figure 1 is a horizontal section through the upper portion of a controller to which my invention has been applied, certain parts of my device being shown in cross section, this view 50 also showing the parts in the position which they assume in the first step of the advancing movement of the lever, and this view illustrates how the device operates to check the movement of the lever; Fig. 2 is a view similar to Fig. 1, but showing how the device releases so as to permit a further advancing

movement of the lever; Fig. 3 is a view similar to Figs. 1 and 2, showing the apparatus in a more advanced step of the releasing movement; Fig. 4 is a vertical section on the line 60 4—4 of Fig. 3; Fig. 5 is a detail view showing a pawl arm and pawl, a portion of the end of the pawl arm being broken away so as to illustrate more fully the details of the means for mounting the pawl; and Fig. 6 is a section 65 through the pawl and pawl arm taken on the line 6—6 of Fig. 5, and further illustrating the details of the pawl mounting.

Referring more particularly to the parts, and especially, to Fig. 1, 1 represents the case 70 of the controller, comprising the usual cover plate 2 and a slightly curved shell 3. The lever spindle 4 passes vertically through the case in the usual manner, and is provided with a star wheel or segment 5, having a 75 plurality of pointed teeth 6 with V-shaped notches 7 therebetween, said teeth being spaced equidistant, as shown. At a suitable point I attach a bracket 8 on the interior of the case, and this bracket is provided with a 80 pawl arm 9 which is pivotally attached to the bracket on a suitable pivot pin 10. This arm is disposed in a horizontal plane and its free end lies near the teeth 6 of the segment. The outer end of this arm is bifurcated and 85 has enlarged eyes 11. These eyes form the bearings for enlarged circular bosses or gudgeons 12 which are formed near the butt end of a pawl 13, which pawl projects away from the segment. Through the gudgeons 90 of the pawl, a pin 14 passes, and this pin constitutes the center pin or arbor for a roller 15. This roller is adapted to engage in the notches 7 and is held in engagement therewith by a coil spring 16 which is attached to the pawl 95 arm and to a hook 17 on the bracket, as shown. The pin 14 is eccentric to the gudgeons 12, so that when the segment is rotated by rotating the spindle 4, the pawl 13 will swing; the direction of movement will be as 100 indicated by the arrows in Fig. 1, or the reverse of these directions, as illustrated in Fig. 2. On the edge of the bracket 8, a stop 17^a is provided, which limits the forward movement of the pawl, as indicated in Fig. 1. The 105 end of the pawl lies near the upper face of the bracket 8 which is horizontal, as indicated, and on this face a rocker block or rocker 18 is mounted on a pivot pin 19. This block has substantially the form shown, 110 It presents a jaw 20 which projects toward the extremity of the arm 9, and this jaw is

separated from the body of the block by a deep slot or throat 21. The jaw 20 does not extend the full width of the block. The inner edge of the jaw which forms an edge of the slot, presents an inclined edge 22, as shown in Fig. 2, beyond which there is presented an abrupt shoulder 23, the purpose of which will be more fully described hereinafter. The edge of the block opposite to the spindle 4 is provided with two depressions or recesses 24, and the edge of the block at this point is rounded, as shown. A small plunger 25 is provided, having a rounded nose which is adapted to engage these depressions, and this plunger is pressed toward the block by a coil spring 26, as indicated in Fig. 1. This plunger evidently will tend to hold the block in either of two positions when it is rocked from side to side by the pawl, as will be described hereinafter.

The free end of the pawl which forms the butt end of the jaw 20, is normally seated in a notch 27 which is formed upon a raised abutment or boss 28 on the upper side of the bracket. The same abutment 28 constitutes a seat for a cam 29 having substantially the form shown. This cam presents a cam edge 30 which projects over the jaw and lies adjacent to the same. The opposite end of the cam is attached to a link 31 which extends toward the right of the controller case, where it is pivotally attached by a pin 32 to a star wheel 33 which is rigidly attached to the reversing spindle 34. This wheel 33 has teeth 35 with V-shaped notches 36 therebetween, as shown. A check arm 37 is provided which is pivoted to the case at 38, and this check arm is provided with a roller 39 at its extremity which is adapted to engage the notches 36 so as to hold the spindle 34 in different positions. These positions correspond to the "off" position of the reversing switch existing when the roller 39 is in the central notch, and correspond also to the "ahead" and reversing positions of said switch, the notch on one side being for the reversing, and the one on the other side being for the "go ahead". This arm 37 is normally held pressed toward the spindle 34 by a coil spring 40 attached to the case, as shown.

The mode of operation of the device will now be described: Referring especially to Fig. 1, when the controller lever 41 (see Fig. 4) is moved from left to right, which is the usual direction of movement for turning the current on, it tends to rotate the spindle 4 in the direction of the arrow shown in Fig. 1. This direction of movement of the segment or star wheel 5 will tend to move the pawl 13 in the direction of the arrow shown adjacent to it, and will swing the pawl until it strikes the stop 17^a, and at this time the end of the pawl will be substantially against the end of the jaw 20, so that the jaw will

prevent the pawl from being displaced outwardly. The roller 15 cannot move out, and acts as a check to the further rotation of the spindle in the direction of the arrow. In this connection it should be noted that in this relation of the parts, the butt end of the jaw 20 is seated in the notch 27, which prevents a rearward movement of the jaw. In this way the advance of the controller lever is checked. In order to free the segment so that it can be rotated in the direction of the arrow shown in Fig. 1, it is necessary to rotate it slightly toward the opposite direction, that is, backwardly, as indicated by the arrow in Fig. 2. When this is done, the free end of the pawl rotates in a right-hand direction, as indicated by the arrow in Fig. 2, and it moves across the mouth of the throat 21, striking against the opposite edge of the throat near the pin 19. The pressure on the block or rocker 18 at this point will tend to rotate it in a left-hand direction on its pivot pin 19, so that the block or rocker 18 will be thrown into the position in which it is shown in Fig. 2. The block or rocker will be stopped in this position by a rounded face 42 which forms a part of the abutment or boss 28 (see Fig. 2). Against this rounded face the outer side or edge of the jaw 20 strikes, as indicated. At this time the nose 25^a of the plunger 25, will have moved into the other one of the recesses 24, that is, into the recess which it does not normally occupy, and it will then tend to hold the block in this position. Now if the direction of the movement of the lever be again reversed so that it is given a forward movement, the end of the pawl will slide out into the throat or slot 21, but as it does so it will rotate across the throat so as to come against the edge 22 of the jaw. A continued movement will then bring the end of the pawl against the shoulder 23, so that when the arm 9 and the pawl 13 have had their full outward movement, the pawl will have pushed the rocker or block 18 back to its normal position, shown in Fig. 1. In making this latter movement, the segment will be released through one notch or tooth space, that is, the next notch in the rear of the one then in engagement with the roller will be moved into engagement with the roller.

In the inner end of the throat 21, a laterally disposed recess or pocket 43 is formed on the edge opposite to the jaw, and this pocket is provided in order to produce clearance for the end of the pawl 13 in performing its necessary motions in the throat.

With the construction described it will be evident that the controller lever can be rotated so as to turn the current on, but the motion cannot be a continuous and sudden one, and the advancing motion will be substantially stopped at each notch 7, necessitating a short pause and a reversal of the di-

rection of movement of the lever. The spring-pressed plunger 25 acts as a clamping device tending to hold the block in either of its outward positions, and it prevents the block from vibrating or being thrown from these positions by the rocking or vibration of the car.

It is desirable that it should be possible for the current to be suddenly turned off from the motor, and in order to prevent any possibility of the rocker checking the rearward movement of the controller lever 41, I have provided the link 31 and the other parts which connect the cam 29 with the reversing spindle 34. If the reversing lever 44 shown in Fig. 4 be swung in the right-hand direction so as to move the link 31 into the position in which it is indicated in dotted lines in Fig. 1, the cam edge 30 will be advanced across the extremity of the jaw 20 and will engage the end of the pawl so as to push it back from the jaw. In this way the pawl is moved out into the throat and the cam edge 30 is made to project over the edge 22 and the shoulder 23 of the jaw. When the spindle 4 is then rotated in the left-hand direction to throw off the current, the pawl 13 simply slides backward and forward in the throat 21, without moving the block and without offering any substantial resistance to the movement of the lever.

The force of the spring 16 can be adjusted by providing several openings 16^a in the pawl 9, in any one of which the end of the spring may be attached. These openings are different distances from the pivot pin 10 of the arm, and consequently give the spring, lever arms of different lengths.

For convenience the pawl 9 is made in two sections 9^a, which enable the gudgeons of the pawl to be made integral with the body thereof. The sections 9^a are then engaged with the gudgeons and are clamped together as will be readily understood.

Having thus described my invention I claim as new and desire to secure by Letters Patent,

1. In combination, a controller spindle, a segment carried thereby, an arm co-operating with said segment, a pawl carried by said arm projecting away from said segment, a member normally adapted to obstruct said pawl when said arm is moved outwardly by said segment and having a slot which may receive said pawl, and means connected with said pawl for directing the same into said slot on a reverse movement of said spindle.

2. In combination, a controller spindle, a star wheel carried thereby, an arm pressed toward said star wheel, a pawl having means for engaging said star wheel at its butt end and projecting away from said star wheel, said pawl being adapted to be swung by the teeth of said star wheel when said segment is rotated, and a movable member con-

trolled by said pawl adapted to check the forward rotation of said segment and adapted to permit a backward rotation of said star wheel.

3. In combination, a controller spindle, a toothed segment carried thereby, an arm, a pawl carried pivotally at the end of said arm and having means at the butt end thereof for engaging the teeth of said segment, said pawl projecting away from said segment, and a pivoted block controlled by said pawl and having a throat adapted to receive said pawl when permitting the rotation of said segment, said block having a jaw adapted to engage said pawl to arrest the movement thereof and check the rotation of said segment.

4. In combination, a controller spindle, a segment having teeth mounted thereupon, an arm, means for pressing said arm toward said segment, a pawl pivotally mounted in the end of said arm, a roller eccentrically mounted on said pawl and engaging between the teeth of said segment whereby the movement of said segment may swing said pawl upon its pivot, said pawl projecting away from said segment, and a block pivotally mounted and adapted to be rocked by said pawl, said block having a throat receiving said pawl to permit a swinging movement of said arm away from said segment, said block affording means for engaging the end of said pawl in another position to prevent an outward swinging movement of said arm, whereby the rotation of said segment is checked.

5. In combination, a controller spindle, a segment having teeth rigidly mounted upon said spindle, a pivoted arm, a spring constraining said arm toward said segment, a pawl pivotally mounted in the end of said arm, a roller eccentrically mounted at the butt end of said pawl and engaging between said teeth, said pawl projecting away from said segment, and a pivoted block having a jaw adapted to engage the end of said pawl when said pawl is actuated by a forward rotation of said segment, said block having an edge adapted to be engaged by said pawl when said pawl is swung by a rearward rotation of said segment, said block having a throat adjacent to said jaw adapted to receive said pawl to permit the rotation of said segment and affording means for replacing said block in its normal position.

6. In combination, a controller spindle, a segment having teeth rigidly attached to said spindle, an arm, means for pressing said arm toward said segment, a pawl pivotally mounted on said arm having a roller at the butt end thereof engaging said teeth and affording means for swinging said pawl when said segment is rotated, a movable block, and means for normally holding said block in position to engage said pawl and prevent the

outward movement of said arm when said segment is rotated forwardly, said block having an edge adapted to be engaged by said pawl in its swinging movement when said 5 segment is reversed, whereby said block is moved to a displaced position, said block having a throat adapted to receive said pawl to permit the outward movement of said arm and the forward movement of said 10 segment.

7. In combination, a controller spindle, a segment having teeth rigidly attached to said spindle, a pivoted arm, means for pressing said arm toward said segment, a pawl pivotally mounted in said arm, a roller carried at the butt end of said pawl and engaging said teeth, said roller enabling said segment to force said arm outwardly and to swing said pawl, and a pivotally mounted block having 15 a jaw engaged by said pawl on the forward rotation of said segment to check the outward movement of said arm, said block having an edge adapted to be engaged by said pawl in its swinging movement when actuated by 20 a backward rotation of said segment, said block having a throat adapted to receive said pawl to permit an outward swinging of said arm with a forward rotation of said 25 segment.

8. In combination, a controller spindle, a segment having teeth rigidly attached to said spindle, an arm, a spring pressing said arm toward said segment, a pawl pivotally carried by said arm, a roller eccentrically 30 mounted on said pawl and engaging between said teeth, and a pivoted block having a jaw adapted to engage the end of said pawl to prevent the outward movement of said arm by said segment, said block having an edge 35 adapted to be engaged by said pawl in its swinging movement to rotate said block and having a throat adapted to receive said pawl to permit an outward movement of said arm, the edge of said throat having a shoulder 40 adapted to engage the end of said pawl whereby said pawl may replace said block.

9. In combination, a controller spindle, a segment having teeth rigidly attached to said spindle, an arm, a spring tending to 45 force said arm toward said segment, a pawl pivotally mounted on said arm, a roller carried by said pawl, engaging between the teeth of said segment, a pivoted block having a jaw, means for holding said block in a normal 50 position in which said jaw will engage the end of said pawl to prevent an outward movement of said arm, said block having an edge adapted to be engaged by said pawl in swinging when actuated by a rearward rotation of said segment, and means tending to 55 60

hold said block in the displaced position in which it is moved by said pawl, said block having a throat adapted to receive said pawl to permit the outward movement of said arm.

65

10. In an electric controller, in combination, a spindle, means for rotating said spindle, a segment carried by said spindle, a member coöperating with said spindle and tending to check the rotation of said spindle 70 periodically as said spindle rotates, means for releasing said spindle from said member by a reverse movement thereof, a reversing spindle, and means for controlling the operation of said member from said reversing 75 spindle.

11. In combination, a spindle, a check device coöperating with said spindle to prevent an uninterrupted forward rotation thereof, said check device comprising a pawl, a member coöperating with said pawl and normally operating to obstruct the movement of said pawl, a reversing spindle, and a connection between said reversing spindle and said pawl 80 for guiding said pawl so as to be unobstructed by said member when said reversing spindle is rotated, whereby an uninterrupted rearward rotation of said first spindle may be 85 had.

12. In combination, a controller spindle, a segment having teeth rigidly attached to said spindle, an arm, means tending to press said arm toward said segment, a pawl carried by said arm, a member normally coöperating with said pawl to prevent the outward movement of said arm and having a throat permitting the outward movement of said pawl, a cam mounted adjacent to said throat and adapted to guide said pawl into said throat, and means for actuating said cam.

90

13. In combination, a controller spindle, a segment having teeth rigidly attached to said spindle, an arm, means tending to press said arm toward said segment, a pawl carried by said arm, a member normally coöperating with said pawl to prevent the outward movement of said arm and having a throat permitting the outward movement of said pawl, a cam mounted adjacent to said throat and adapted to guide said pawl into said throat, 95 a reversing spindle, and means for actuating said cam from said reversing spindle.

105

In testimony whereof I have signed my name to this specification in the presence of two subscribing witnesses.

JOHN THOMAS.
